REFLECTIVE ROADWAY MARKER

Howard A. Schaefer, Lancaster, Ohio, assignor to Anchor Hocking Corporation, Lancaster, Ohio

Filed Apr. 25, 1973, Ser. No. 354,177

Term of patent 14 years

Int. Cl. D29—02

U.S. Cl. D72—1 J

FIG. 1 is a top plan view of a reflective roadway marker showing my new design;

FIGS. 2—5 are front elevation, bottom plan, rear elevation and side elevation views, respectively, of the reflective roadway marker shown in FIG. 1; and

FIG. 6 is a cross-sectional view taken through FIG. 1 along the line 6—6.

I claim:

The ornamental design for a reflective roadway marker, substantially as shown and described.
